UNITED STATES PATENT OFFICE.

CHARLES F. L. KING, OF EDGECASTON, BIRMINGHAM, ENGLAND.

FUEL-SUPPLY APPARATUS FOR INTERNAL-COMBUSTION ENGINES.

1,321,756

Specification of Letters Patent.

Patented Nov. 11, 1919.

Application filed June 5, 1918. Serial No. 238,371.

To all whom it may concern:

Be it known that I, CHARLES FREDERICK LAWRENCE KING, a subject of the King of Great Britain, residing at 138 Bristol road, 5 Edgbaston, Birmingham, England, have invented certain new and useful Improvements in Fuel-Supply Apparatus for Internal-Combustion Engines, of which the following is a specification.

10 This invention relates to fuel supply apparatus for internal combustion engines of motor vehicles and the like, said apparatus being of that type in which a low level supply tank is employed from which liquid fuel 15 is raised by suction into an auxiliary receptacle from which it flows by gravity to the carburetor; the suction and air valves being controlled by a rising and falling float.

20 The object of the present invention is to provide an improved and simplified form of valve mechanism.

According to the said invention the suction and air valves are of the piston valve type, and are carried upon a single rod or 25 stem operated from the float, preferably through a suitable lever, means being provided for allowing an idle movement to the float until it reaches its extreme raised and lowered positions so as to insure the suction 30 valve remaining open and the air valve closed while the float is rising and the said suction valve remaining closed and the air valve open while the fuel is being discharged.

35 Figure 1 of the accompanying drawings represents a vertical section through an apparatus in accordance with this invention. Fig. 2 represents a modification.

The apparatus shown in Fig. 1 comprises 40 a float 1 mounted to slide upon a guide rod 2 between stop pins 3, 4; or the float may be fixed upon the rod. The upper end of the latter is pivoted to the longer arm 5 of a bell-crank lever fulcrumed at 6 to a bracket 45 7 within the upper part of the receptacle 8. The other or short arm 9 of this lever is arranged substantially vertically and engages within a slot or recess 10 formed in a cylindrical part or actuating head 11 attached to a horizontally sliding valve rod 12 located in a housing in the cover 13 of the receptacle. This rod 12 carries the suction and air valves 14, 15, which are in the form of cylindrical piston valves. The suction 55 valve 14 moves in a chamber 16 having a port 17 leading to the suction pipe and be-

tween the suction valve chamber 16 and the chamber 18 containing the actuating head, is a passage 19 of rather larger bore than the diameter of the valve rod 12 and from which a port 20 leads into the receptacle 8. When the suction valve 14 is in a position such that the port 17 leading to the suction pipe is uncovered, as in Fig. 1, the air can be withdrawn from the receptacle 8 through the port 20 and through the valve rod passage 19 into the suction valve chamber 16 and thence through the suction pipe. On the closing of the valve it first covers the port 17 leading to the suction pipe and then closes on to its seating 21 at the end of the valve chamber.

The air valve 15 works in a cylindrical passage 22 open to the atmosphere at one end and communicating at the other end, 75 when the valve is withdrawn, with an enlarged chamber 23, which is in communication with the interior of the receptacle by a passage 24. When the valve 15 is within the cylindrical passage 22 the air is cut off, 80 but as soon as its outer end leaves said passage and enters the enlarged chamber 23 (which happens when the suction valve 14 closes on to its seating) the air suddenly 85 rushes into the receptacle.

The end of the actuating head 11 of the valve rod is always subjected to atmospheric pressure by means of an opening or openings 25 in the chamber 18 in which it moves.

The operation of the apparatus is as follows:—Assuming the suction valve 14 to be open, as shown in Fig. 1, and the air valve 15 closed, air is withdrawn from the receptacle, which thus fills with fuel through a suitable inlet. As the float 1 rises it engages with stop 3 causing the short arm 9 of the bell-crank lever to move idly within the slot or recess 10 in the actuating head 11 of the valve rod until the said float has nearly reached its highest position, when 100 said arm 9 engages with the end of the slot or recess and moves the valve rod 12, causing the suction valve 14 first to close the port 17 leading to the suction pipe, and then to move fully onto its seating 21. At the same time the air valve 15 is withdrawn from its cylindrical passage into the enlarged chamber 23, thus admitting air to the receptacle. The fuel is then discharged from the outlet 105 26 past the flap valve 27 into the outer chamber 28, whence it passes to the carburetor. The float falls, but owing to the idle move-

ment allowed by the slot or recess 10 in the actuating head of the valve rod, and by the stops 3, 4, on the guide rod, the valves remain in the position described until the fuel 5 has descended to a predetermined level, when the short arm 9 of the bell-crank lever engages with the opposite end of the slot or recess 10 and moves the valve rod 12 in the opposite direction, closing the air valve and 10 opening the suction valve, the receptacle thus re-filling.

If the float be fixed upon the rod 2 the idle or lost movement may be provided for entirely by the slot 10. It may, however, 15 be obtained as shown in Fig. 2, where the rod 2 having the float fixed to it, carries a pin 29 sliding in a slot 30 in a sleeve 31 pivoted to the end of the longer arm 5 of the bell-crank lever, the shorter arm 9 engaging 20 within a recess 10 in the head 11 without idle movement therein.

Where the float slides on the rod the whole of the idle movement may be obtained by the float moving between the stops on 25 said rod.

Having fully described my invention, what I desire to claim and secure by Letters Patent is:—

1. A fuel-supply apparatus comprising a 30 low-level reservoir, an auxiliary receptacle communicating with the low-level reservoir, a source of suction, a cover to the receptacle provided with a valve housing having ports communicating with the source of suction 35 and the atmosphere and air and suction ports leading to the receptacle, piston-type air and suction valves carried by a horizontally 40 sliding stem within the housing for controlling said ports, a float, a lever operated by the float and engaging with the valve

stem, and a lost-motion connection between the float and the valve stem.

2. A fuel-supply apparatus comprising a low-level reservoir, an auxiliary receptacle communicating with the low-level reservoir, 45 a source of suction, a cover to the receptacle provided with a valve housing having ports communicating with the source of suction and the atmosphere and air and suction ports leading to the receptacle, piston-type air and 50 suction valves carried by a horizontally sliding stem within the housing for controlling said ports, a float, a head on the valve stem provided with a recess, a lever operated by the float and having one arm engaging the recess in the head of the valve stem, and a lost-motion connection between the float 55 and the valve stem.

3. A fuel supply apparatus comprising a low-level reservoir, an auxiliary receptacle 60 communicating with the low-level reservoir, a source of suction, a piston-type suction valve sliding in a chamber communicating with the source of suction and with the receptacle, an air valve sliding within an open 65 chamber leading to an enlargement communicating with the receptacle and adapted to move into said enlargement, when the suction valve is closed, so as to place said receptacle in communication with the atmosphere, a stem carrying both air and suction 70 valves, a float, and a lost-motion connection between the float and the valve stem.

In testimony whereof I have hereunto set my hand in presence of two subscribing 75 witnesses.

C. F. L. KING.
